UNITED STATES PATENT OFFICE.

WOUTER POLDERMAN, JR., AND FRIDOLIN HEINRICH LUCHSINGER, OF YMUIDEN,
NETHERLANDS.

SMOKE AND WATER TUBE BOILER.

1,161,726.

Specification of Letters Patent. Patented Nov. 23, 1915.

Application filed April 12, 1915. Serial No. 20,941.

To all whom it may concern:

Be it known that we, WOUTER POLDERMAN, Jr., and FRIDOLIN HEINRICH LUCHSINGER, subjects of the Queen of the Netherlands, and both residing at Prins Hendrikstraat 15-19 Ymuiden, Netherlands, have invented new and useful Improvements in or Relating to Smoke and Water Tube Boilers; and we hereby declare the following to be a full, 10 clear, and exact description of the same.

This invention relates to improvements in combined smoke- and water-tube boilers, in which the water spaces around the ordinary combustion chambers are dispensed with and water tubes are substituted for them, such tubes being arranged so as to extend upwardly from a large transverse horizontal water pipe connected to the bottom space of the boiler up to the water level, or 15 steam chamber, above the fire tubes. These water tubes are also arranged close to one another in such a manner as to form a substantially solid and continuous wall or walls of water-tubes inclosing the said combustion 20 chamber or chambers and are curved slightly vertically.

In known arrangements the afore-mentioned water tubes enter the rear vertical plate of the boiler and inclose the combustion chamber at the top, in consequence of which they must be curved considerably and cannot be removed without destroying the bricking in of the combustion chamber. Furthermore the horizontal or nearly horizontal 25 portions of the water tubes caused by the tubes entering the rear plate as afore-said, form an impediment to the generation of steam in the tubes as they hinder the free rising of the steam bubbles and finally they 30 are very liable to be burnt in consequence of the deposit of scale and the like. According to this invention these various objections are avoided by employing approximately vertical water tubes for forming the rear 35 wall of the combustion chamber, said tubes entering at their upper end a part of the top space of the boiler which overhangs the combustion chamber. The bottom plate of this overhanging part is the crown plate of the 40 combustion chamber and has the shape of a horizontal letter S one curve of which is connected to or forms a continuation of the

rear tube plate, while the other curve is connected to or forms a continuation of the rear end plate of the overhanging part of the 45 boiler. The first mentioned curve is somewhat smaller than the other curve.

The crown plate of the combustion chamber does not require any reinforcement, such as crown bars or the like, owing to its shape. 50

The invention may be also applied to double boilers. In this case the bricking in of the water tubes can be dispensed with, the tubes being placed in a row or rows in the middle of the combustion chamber, inclosed 55 between the rear tube plates of the two halves of the installation and the bottom of the upper part of the boiler, which connects the two halves. Said bottom constituting the crown plate of the combustion chamber 60 is cylindrically bent downward in the middle and connected to the rear tube plates by means of curves with a small radius, so that in the case of the double boiler also the construction is sufficiently rigid in itself and 65 crown bars or the like may be omitted.

At the bottom end, the water tubes are connected to a transverse drum as usual in this type of boiler, said drum communicating with the interior of the boiler below the 70 grate level, in the case of a double boiler with the two halves of the installation.

The invention further resides in certain features of construction, arrangement and combination of parts hereinafter more fully 75 described and pointed out in the appended claims.

In the drawings which form a part of the specification Figure 1 is a rear end view of the boiler constructed in accordance with the 80 invention, and Fig. 2 is a side sectional view taken on the line 2-2 of Fig. 1.

Like reference characters denote similar like parts throughout the specification and drawings. 85

Referring to the showing in Figs. 1 and 2, 4 indicates a boiler shell and is substantially cylindrical in cross-section. The rear tube plate 1 of the boiler is bent intermediate its length into an S formation and provides 90 a crown plate lying directly over the combustion chamber, as shown at 3. One of the curved ends of the S-shaped crown plate 3 has a greater radius than the other curved 95

end, the end having the greater radius having its convexed portion facing downwardly and the other or smaller end of the plate 3 having its concaved end facing downwardly. 5 Owing to the shape of the crown plate 3, it is not necessary to connect the same in the usual manner by means of crown bars and stay bolts to portions of the boiler shell 4. The boiler 4 is provided near its bottom with 10 a flue or fire box 9 having disposed therein the fire bridge 7.

The peculiar formation of the rear tube plate 1 forms a recess in the rear end of the boiler, as will be clearly seen from Fig. 15 2, which recess provides the combustion chamber 2. Disposed under the crown plate 3 and opposite the flue or fire box opening 9 is a transversely extending water drum 6. A plurality of upwardly extending pipes 20 5 nested close together in juxtaposition and extending from the drum 6 into the curved end of the crown plate 3 having a greater radius, thus communicating the water drum with the boiler 4 substantially at the water 25 level of the boiler and above the fire tubes 10. The nest of tubes 5, as before stated, are nested in close relation and are adapted to provide a solid and continuous rear wall for the combustion chamber 2 formed by the 30 curvature of the rear tube plate 1. These tubes 5 are also curved slightly vertically which increases the strength of the structure and also increases the heating surface of the back wall. The side walls of the 35 combustion chamber 2 may be formed of masonry or other suitable fireproof material, as shown at 2^a, and the back wall of the combustion chamber 2, formed by the tubes 5, may have a suitable backing of non-heat 40 conducting and fire-proof material, as shown at 2^b. It will thus be seen from the above that the crown plate 3 lies directly over the combustion chamber and that the nest of tubes 5 extending from the transverse boiler 6 45 form the back wall of the combustion chamber 2.

The fire tubes 10 are disposed in and secured to the boiler 4 above the fire box 9 in any suitable or approved manner and have 50 communication with the combustion chamber 2 through the rear tube plate 1. It will also be seen that a slight curvature in the pipes 5 provides a means for directing the particles of combustion and smoke into the 55 smoke tubes 10, and produces a strong upward circulation of the water through the water tubes to the boiler.

Connecting the portion of the boiler below the fire box 9 with the water drum 6 is 60 the elbow water connecting tube 8 centrally secured to the water drum 6. Centrally extending in the lower portion of the boiler 4 and forming a continuation of the tube 8 is the tube 11 terminating in the middle of the

boiler and having its inner and free end cut 65 at an angle so as to provide an enlarged entrance opening for the water into the tube. The circulation of water in the boiler is as follows: From the water tube 11, drum 6, through the tubular wall 5, the upper portion of the boiler 1 and then downwardly 70 through the boiler, contacting with the fire tubes 10 and fire box 9. It will be obvious that the disposition of the tube 11 permits an even circulation of the water since the 75 latter will be equally drawn from the front and rear ends of the boiler, thus preventing a particular circulation in the rear portion of the boiler.

Having thus described my invention, it is 80 believed that a full and clear understanding of the same will be had, however, certain changes as to the exact and precise construction may be resorted to that fall within the scope of the appended claims.

What we claim is:

1. A steam generating device comprising a boiler having the rear wall thereof recessed, a fire box extending through the lower portion of said boiler and communicating with the recess, a transverse water drum supported within the recess and opposite said fire box, a plurality of closely nested, juxtaposed water tubes extending upwardly from said water drum and communicating the latter with the boiler, said nest of tubes forming a solid and continuous rear wall for the boiler and combustion chamber, side walls for said combustion chamber of fire-proof material, a backing of fire-proof material in immediate engagement with said tubes and extending the length of the latter, a fire bridge in said fire box and a bottom wall for said combustion chamber extending between said fire bridge and said water drum, an elbow water connection between said water drum and the portion of said boiler below said fire box, a tube forming a continuation of said elbow connection and extending within said boiler to a central point thereof, and fire tubes extending through the portion of the boiler above said fire box and communicating with said combustion chamber.

2. A steam generating device comprising a boiler having the rear wall thereof recessed to form the combustion chamber, a fire-box extending through the lower portion of said boiler and communicating with the recess, a transverse water drum supported within the recess and opposite said fire-box, a plurality of closely nested juxtaposed water tubes extending upwardly from said water drum and communicating the latter with the overlying wall of the boiler, said nest of water tubes forming a solid and continuous rear wall for the boiler and combustion chamber, side walls for the combustion chamber of fire-proof material, and a

backing of fire-proof material in immediate engagement with said tubes and extending the length of the latter, said water tubes being curved outwardly from the boiler intermediate their ends, for the purpose described.

In testimony whereof we have signed our

names to this specification in the presence of the two subscribing witnesses.

WOUTER POLDERMAN, JUNIOR.
FRIDOLIN HEINRICH LUCHSINGER.

ANTONINO NAGLEGRUG,
I. I. HELSDON ROX.
